FIRE CONTROL APPARATUS FOR CONTROL-
LING THE FLIGHT OF MISSILESPaul B. Hunter, Metuchen, N. J., assignor to The
Sperry Corporation, Great Neck, N. Y., a corpora-
tion of Delaware

Application May 3, 1945, Serial No. 591,727

3 Claims. (Cl. 89—41)

1

This invention relates, generally, to the use of ultra-high frequency radio waves for controlling bombs and other explosive missiles such as rocket missiles, aerial torpedoes, shells, etc., after the same have been discharged from their releasing or projecting apparatus and during flight. This application is a continuation-in-part of Patent No. 2,414,103, granted January 14, 1947, for Apparatus for Controlling a Missile in Flight.

Owing to the constantly increasing height at which military aircraft navigate, it is highly desirable to control explosive projectiles or missiles such as bombs, aerial torpedoes, shells, rockets, etc., after they have left the airplane or the ground as the case may be, in order to correct for the initial sighting errors and other errors including drift errors due to variation of side winds at varying altitudes. Thus, in firing at an aerial target from a ground installation, initial errors present at the time of the projection of the missile are generally augmented by the variations of the missile trajectory due to such things as wobbling of the missile, variation in the wind direction and speed with changing altitude or change in the speed or direction of movement of a moving target.

The principal object of the present invention is to provide novel apparatus for controlling bombs, and other explosive missiles such as rocket missiles, aerial torpedoes, shells, etc., after the same have started their courses and in continuing such control until the target is actually reached by the missiles whereby the latter are caused to hit the target or to explode at substantially their nearest approach thereto.

Another object of the present invention is to provide an ultra-high frequency transmitter adjacent the point at which the shell or other missile is released, the missile being equipped with suitable ultra-high frequency radio receiving apparatus and a servo-mechanism controlled therefrom for effecting transverse movement of the missile in accordance with signals received from the transmitter.

A further object of the present invention is to provide fire control means wherein a gun is directed in accordance with the predicted future position of target as obtained from a fire control predictor, radio means being provided for con-

2

trolling the gun projectile after the same leaves the gun and for directing the same onto the target.

A further object of the invention is to provide means for utilizing the position data of a target as determined by an anti-aircraft fire director for positioning the electromagnetic beam radiating means so that the projectile will traverse a trajectory leading to the predicted future position of the target thereby eliminating the necessity of the projectile chasing the target.

Other objects and advantages will become apparent from the specification, taken in connection with the accompanying drawings wherein the invention is embodied in concrete form.

In the drawings,

Fig. 1 is a schematic view illustrating one use of the apparatus of the present invention.

Fig. 2 is, in part, a sectional view of a projectile equipped with a position sensitive receiver and servo-mechanism.

Fig. 3 is a graph illustrating the system of Figs. 1 and 2.

Fig. 4 is a sectional view along line 4—4 of Fig. 2.

Similar characters of reference are used in all of the above figures to indicate corresponding parts.

In Fig. 1 there is diagrammatically illustrated a typical embodiment of the present invention wherein an anti-aircraft fire director, generally designated by numeral 11, is employed for controlling the orientation of a radiating antenna means 13 and the fire of a universally mounted missile launching device or propellant here shown as a gun 14. The antenna means 13 is fed from an ultra-high frequency transmitter 15 as of the type disclosed in Patent No. 2,242,275 of R. H. Varian dated May 20, 1941, for delivering to a transmitter antenna 17, ultra-high frequency carrier waves having a frequency of the order of 10^{10} cycles per second, such waves being subject to propagation in substantially straight lines and also having the property of penetrating fog, etc. and not being appreciably interfered with by uncontrollable natural phenomena such as atmospherics or radiation from the sun. The antenna 17 is shown provided with a parabolic reflector 19 which has a diameter preferably twenty or more times the wavelength used,

whereby this reflector has high resolving power and produces a highly directional beam of electromagnetic energy. The reflector 19 is shown carrying a telescope 21 that has its line of vision parallel to that of the electromagnetic radiation beam projected from the antenna 17. The telescope 21 is rigidly mounted on reflector 19 for conjoint movement therewith for a purpose to be described below.

It is known that, even with the most highly developed types of fire control directors, the percentage of direct hits or near misses obtained is relatively low. This fact is, in a large measure, due to conditions which are beyond the control or influence of the director system, as for example, the failure of the target to maintain constant flight path, or variation in conditions encountered by the missile in flight. In accordance with the present invention, remote control radio means are provided for inserting a correction in the path of a missile which is observed by means of telescope 21 to be "off target." The correction is introduced at a time when the missile nears its closest approach to the target, so that an otherwise complete miss may be converted to a direct hit or a near miss. Such a correction is inserted under the influence of the highly directional beam of electromagnetic energy produced by the antenna means 13 and transmitter 15, coaxing with the radio-controlled missile illustrated in Fig. 2 and particularly described in the above-mentioned Patent No. 2,414,103.

In the event of bombardment through the overcast, the telescope 21 may be omitted and the observation of the missile may be made by a suitable radio direction and range indicating system of the type described in copending application Serial No. 406,494, filed August 12, 1941.

As shown in Fig. 1, the anti-aircraft fire director 11, which may be of any conventional type, as for example, that disclosed in Patent No. 2,065,303 for Apparatus for the Control of Gunfire, supplies target position data to the gun 14 through cable 23 and a conventional servo mechanism 25 for control in azimuth and through cable 27 and a conventional servo mechanism 29 for control in elevation.

The output of the azimuth servo 25 is operatively coupled to the gun 14 by means of a shaft 31 and gear 33 that meshes with the teeth of a ring gear 35 rigid with a turntable 37 on which the gun 14 is mounted for azimuthal movement. Similarly, the output of the elevational servo 29 is operatively coupled to the gun 14 by means of shaft 39, gears 41, 43 and shaft 45 which is adapted to move the gun 14 in elevation. In this way, when the director is correctly operated, the gun 14 is correctly oriented to project the missile to intercept the target at its future position.

The antenna means 13 is mounted on a turntable 47 for simultaneous azimuthal rotation with the gun turntable 37, said turntable 47 being coupled to the table 37 by gear 49 in mesh with ring gear 51 which is rigidly connected to the table 47. Gear 49 is driven by shaft 53 which in turn is coupled through gear 33 and friction slip clutch 55 to shaft 31. Gears 51, 59 together with friction slip clutch 61 and shaft 63 operatively connect antenna means 13 to shaft 39 for simultaneous elevational movement with the gun 14.

For the purpose of producing relatively fine movement of the antenna means 13 in order to insert the above-mentioned slight correction in the trajectory of the missile, there are provided

hand cranks 65, 67, which through gears 66 and 69 and the slippage of the clutches 55, 61, respectively, make possible azimuthal and elevational movement of the antenna means 13 without affecting the position or movement of gun 14.

While the operation of the improved fire control system will hereinafter be described in connection with a radio control missile 71 shown in Fig. 2, it is to be understood that the present invention is not limited or restricted to this particular type of missile, since other types, as for example, those illustrated, described and claimed in copending applications Serial No. 468,308, filed December 7, 1942, and Serial No. 591,724, filed concurrently herewith, may be used with equally satisfactory results.

While the target is being tracked by an observer operating the fire control director 11 and the gun 14 is being positioned in accordance with information derived from the director and transmitted to the gun table through the servo mechanisms 25, 29, the missile 71 is launched so as to put it at the predicted future position of the target. A radio control operator energizes the antenna means 13 as the missile nears the target producing a highly directive beam of electromagnetic energy, as graphically shown in Fig. 3, and at the same time observes the target through the telescope 21. If the observer notices, that, as the missile nears the distance of closest approach with the target, a complete miss is about to be experienced, the observer may, by means of the hand cranks 65, 67, shift the position of the antenna means to insert a slight correction in the missile's trajectory, steering it enough to put it on or very close to the target.

The ultra-high frequency radio output of the transmitter antenna means 13 is adapted to be received by four antennae, three of which are shown at 73, 75 and 77, carried by the missile 71.

Antennae 73, 75 are spaced an appreciable distance apart as by placing these antennae on the outer edges of opposed fins 79. Similarly, the antennae 77 and a similar one (not shown) are spaced appreciably apart as by being located on the outer edges of fins 81 extending at right angles to the plane of fins 79 carrying antennae 73, 75.

In Fig. 2 the antennae 73, 75 are shown as dipoles connected through concentric lines 83, 85 to any conventional multichannel radio receiver 86, the outputs of which are connected respectively to solenoids 87, 89 arranged for opposite actuation of armatures 91, 93 connected to pistons 95 of a balanced valve 97. The central portion of valve 97 is supplied with compressed air or carbon dioxide gas from a tank 99 through pipe 101. When carbon dioxide is used it may be carried in liquid form in tank 99. Valve 97 has two upper pipes 103 and 105 that have their outer portions extending radially within the cylindrical body of the missile 71 in opposite directions, the common axis of these portions of the pipes 103, 105 passing preferably through the center of gravity of the missile. The outer ends of the pipes 103, 105 project through the housing of the missile for delivering compressed air or carbon dioxide gas in opposite directions diametrically of the missile. The radial portions of pipes 103, 105 lie in the vertical plane also containing the spaced antennae 73, 75.

The antennae 77 and the one diametrically opposed thereto are similarly connected to a receiver circuit, such as shown in Fig. 2 for controlling the operation of solenoids 107, 109, shown

in Fig. 4, the armatures of these solenoids being employed for operating the balanced valve 111 similar to valve 97, valve 111 controlling the flow of compressed air from the pipe 101 to two outwardly extending pipes 113, 115 extending through the wall of the missile 71 for directing air or carbon dioxide blasts in diametrically opposite directions. The radial portions of pipes 113, 115 lie in the plane of the corresponding antennae.

After projecting the missile and before the same has reached its target the radio observer looks through the telescope 21 and observes the target.

As the missile approaches the target, the latter moves into the field of vision of the observer looking through the telescope 21 although the target is probably not in the central line of sight of the telescope at this time. If the transmitter 15 is producing a pencil beam of ultra-high frequency electromagnetic radiation the field intensity of any cross section of which is greatest at the center of the beam and tapers off in substantially the fashion shown in Fig. 3 to the side edges thereof, the missile will ordinarily line itself up with the center of the beam. Assuming that the missile is not initially lined up with the center of the beam then due to the varying field intensity of the beam across its cross section one of the antennae 73 or 75, for example, will receive more energy than the other, so that the output of one channel of receiver 86, for example, will be made greater than that of the other channel, whereby solenoid 87 is energized to a greater extent than solenoid 89 so that the balanced valve 97 is moved to uncover pipe 103 thereby causing tank 99 to discharge compressed air or gas through valve 97 and pipe 103 and effecting a movement of the missile toward the center of the radiating beam, i. e., toward the left in Fig. 3. Similarly, if antenna 77, for example, should receive more energy than its diametrically opposed antenna it would act to shift the missile transversely in the plane of these antennae to bring the missile into the central axis 117 of the radiating beam corresponding to the center of the line of sight of the telescope 21. Just before the projectile is about to strike the target, the radio observer gradually shifts the telescope 21 and the antenna means 13 angularly by means of hand cranks 65, 67 so as to bring his line of sight and hence the missile into the direct line of the target so that the latter will be hit as desired.

It will be noted from Fig. 3 that as long as the missile is lined up with the center of line 117 of the radiating electromagnetic beam, the antennae will receive equal intensity of signal so that the balanced valves 97, 111 will be held in their neutral positions so that the outputs of the various amplifiers will be equal. Should the missile commence to move out of the center of the beam the antennae will receive signals of unequal strength resulting in the operation of the servo-mechanism and the movement of the missile transversely back into the center of the radiating beam. Owing to the high pressure of the air or gas within the tank 99 and to the fact that the period of time of flight of the missile is short, the flow of air or gas through pipes 103, 105 and 113, 115 is quite rapid so that the reaction force of the jets issuing from these pipes is large, thereby resulting in an immediate response of the missile to any deviation of the same from the path of the beam effect-

ing a rapid return of the missile to the beam.

To further increase the probability of direct hits or near misses, a radio-controlled automatically detonated missile of the type described in copending application Serial Number 468,308, filed December 7, 1942, may be utilized.

There has thus been described an improved fire control system whereby a missile may be launched at a target in accordance with information derived from fire director means and, when it is observed that a complete miss is to be experienced, a correction in the trajectory of the missile may be introduced to direct the missile toward the target.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. Fire control apparatus for controlling the flight of missiles comprising means for projecting a missile, a computer for positioning said projecting means for causing the missile to follow a desired predicted course for obtaining collision with a target, means for sighting the missile and the target as these elements approach each other, and means for projecting a pencil beam of electromagnetic energy toward the missile and target, said beam having a field intensity which is a maximum along its axis and tapers off progressively at successive points removed therefrom, said missile having steering means responsive to variations in the field intensity of said beam and means for adjusting said beam projecting means for correcting the direction of said pencil beam and the course of said missile to produce a collision course between said projectile and the target.

2. Fire control apparatus for controlling the flight of missiles comprising means for projecting a missile, a fire control computer for positioning said projecting means for causing the missile to follow a desired predicted course for obtaining collision with a target, means for sighting the missile and the target as these elements approach each other and for determining a correction course for the missile, and means for projecting a pencil beam of electromagnetic energy toward the missile and target, said beam having a field intensity which is a maximum along its axis and tapers off progressively at successive points removed transversely therefrom, said missile having steering means responsive to variations in the field intensity of said beam and means for adjusting said beam projecting means for correcting the direction of said pencil beam and the course of said missile to produce a collision course between said projectile and the target.

3. Fire control apparatus for controlling the flight of missiles comprising means for projecting a missile, a fire control computer, a servo mechanism connecting said computer to said missile projecting means for positioning the latter to cause the missile to follow a desired predicted course, telescopic means for sighting the missile and a target and for determining a correction course for the missile, a directional electromagnetic radiator for projecting a pencil beam of electromagnetic energy toward the missile and target, said beam having a field in-

tensity that is at its maximum along its axis and tapers off progressively transversely therefrom, radio receiver and servo mechanism on said missile for steering the same in response to variations in the field intensity of said beam, and manually controlled means for adjusting said beam radiating means for correcting the direction of said pencil beam and hence the course of said missile to produce a desired collision course between the target and the missile.
